ATTORNEY

UNITED STATES PATENT OFFICE.

EMMETT O. LOVELAND, OF KANSAS CITY, MISSOURI, ASSIGNOR OF ONE-HALF TO R. A. SMALLFELDT, OF KANSAS CITY, MISSOURI.

ELECTROTYPE PLATE.

Application filed January 20, 1926. Serial No. 82,460.

My invention relates to electro-types and more particularly to a plate of that character for use on multigraph machines, the principal object of the invention being the making of a more rigid and accurate electro-type of this kind to eliminate defacement of the printed sheet through contact with blank spaces between the printing matter, and to eliminate uneven curvature of the plate.

In accomplishing this and other objects of the invention I have provided improved details of structure, the preferred forms of which are illustrated in the accompanying drawings wherin:

Fig. 1 is a perspective view of an electro-type embodying my improvements, and illustrating its application to a segment of a multigraph machine.

Fig. 2 is a central, longitudinal section of a plate constructed according to my invention.

Fig. 3 is a transverse section of the same.

Fig. 4 is a detail perspective view of the finished plate elements.

In making plates of this character it is customary to first set up the type or other matter to eventually appear in the electro-type, take an impression in wax and then electroplate the wax. Then the plate is removed from the wax and backed by lead or other soft metal in a manner well known in the practice of this art.

The rough plate is then dressed down and curved to fit the periphery of a segment constituting a part of the multigraph machine or press.

The mold on which the electro-type is deposited comprises means for forming lips on the ends of the plate over which bands are applied to attach the plate to the segment. As the plate can only be of a limited thickness and must be of sufficient body to carry the solid portions which are to be reproduced and to provide the attaching lips, it not infrequently occurs that the sheets printed in the machine are drawn into the open spaces between the printed matter and become smudged by contact with the back of the plate. It also frequently happens

that the open spaces between the type or cut matter on a plate extends in such longitudinal arrangement that the plate is weakened along a sufficiently definite line that it bends unevenly so that it cannot fit smoothly on the multigraph segment, with the result that an imperfect impression is made on the printed sheet.

It is to overcome these disadvantages in the ordinary type of plate that I have devised my improvements which consist generically in elimination of a maximum amount of the electro-type metal and substituting therefor a back plate which is sweated onto the electro-type plate after the latter has been dressed, the backing plate also providing the end lips whereby the plate is attached to the segment by an attaching band of ordinary construction.

In the drawings:

1 designates an electro-type made in the ordinary manner except as to thickness and length, the thickness being reduced to that sufficient to stabilize the type or cut matter and the length being reduced to that of the ordinary plate minus the end lips.

With the plate dressed to this thickness and length, and while still flat, a backing plate 2, preferably of tin plate, although it may be of any other suitable metal, is attached to the back of the electro-type by sweating or otherwise, to form a permanent part of the electro-type, the backing plate being of sufficiently greater length than the electro-type to provide the end lips 3.

When the two plates have been thus assembled they are curved to fit the segment 4 of the multigraph machine, the combined thickness of the electro-type and backing plate 2 corresponding to the usual thickness of an electro-type so that it will operate properly on the printing machine or press, and the lips 3 serving to carry the band 5 whereby the plate is secured to the segment.

It is apparent that with my improvements the comparatively soft metal electro-type may be of substantially the same thickness as the ordinary plate, but can be cut away to a greater depth for the open spaces about the type and cut matter, the backing plate

being sufficiently thin to avoid excessive projection within the printing face of the plate, but because of its greater density and strength, serving to hold the electro-type 5 to its proper formation.

What I claim and desire to secure by Letters-Patent is:—

1. An electro-type comprising a body plate having a printing surface, and a sheet 10 metal backing plate of different material,

permanently secured to the rear face of the body plate.

2. An electro-type comprising a body plate having a printing surface, and a thin backing plate of relatively stiff sheet metal, 15 permanently secured to the rear face of the body plate and projected beyond the ends of the body plate to form band lips.

In testimony whereof I affix my signature.

EMMETT O. LOVELAND.
